WASHING MACHINE

Henry J. Rand, Bratenahl, Ohio, assignor to H. J. Rand Washing Machine Corp., Bratenahl, Ohio, a corporation of Ohio

Application January 31, 1948, Serial No. 5,628

8 Claims. (Cl. 68—21)

1

This invention relates to improvements in a vacuum breaker for use in connection with washing machine of the type in which a flexible bag is collapsed against the laundry to squeeze the detergent out of the same.

One of the objects of the present invention is to provide means for automatically breaking the vacuum in the type of washing machine mentioned above after each vacuum drying operation.

Another object of the present invention is to provide novel control means for the flow of liquid and air into and out of a washing machine of the vacuum drying type.

Other objects and advantages of the present invention will be apparent from the accompanying drawings and description and the essential features will be set forth in the appended claims.

In the drawings,

Fig. 1 is a central sectional view through a washing machine equipped with my invention;

Fig. 2 is an enlarged fragmental sectional view showing the central portion of Fig. 1 in greater detail;

Fig. 3 is a fragmental sectional view taken along the line 3—3 of Fig. 2, while

Figs. 4 and 5 are similar to Figs. 2 and 3 respectively, showing different condition of the parts.

In order to use vacuum drying in connection with washing machines, it is desirable that the apparatus be so arranged that if a vacuum should occur within the supply line, no contaminated water could be carried out of the washing machine into the supply line. The present invention accomplishes this in a washing machine of the type more fully disclosed and described in my copending application, Serial No. 682,322, filed July 9, 1946, Patent No. 2,472,682, to which reference may be had for a more complete description.

The machine here shown comprises a flexible bag 10 which is supported within a suitable wall 11. Suitable means is provided centrally of the bag 10 for causing a washing action of the laundry placed therein. The bag has an open neck 10a through which laundry and soap are introduced. A cover 12 is provided for this opening and the cover carries a seal 13 adapted to produce an air tight joint when vacuum is produced within the bag for a drying operation. This sealing device is more fully disclosed and claimed in my copending application, Serial No. 5,623, filed January 31, 1948. The cover here shown utilizes a spacing ring 14 which is rigidly connected with an inner cover member 15 which fits

2

down into the neck of the bag. In the present form of my device, liquid is introduced into the bag 10 through flexible rubber tubing 16. This tubing fits tightly into the opening 17 where it passes through the spacing ring 14 so as to permit a good vacuum to be drawn within the bag, as will later appear. It should be understood that the rubber tubing at least at the zone 16a is molded in the forms shown in Figs. 4 and 5. In other words, the normal condition of the tubing at this point is flat with no opening in the center. The free end of the rubber tube is provided with an elbow 16b turned downwardly within a sleeve member 18 which opens to the interior of the bag 10. Tubing 16 is mounted through sleeve member 18 in an air- and liquid-tight manner, such as by the provision of suitable securing gaskets or other means well-known to those skilled in the art. It is thus apparent that water introduced through the tube 16 will pass downwardly through the sleeve member 18 into the bag for the purpose of filling the same. It will be noticed in Fig. 1 that the open end of the elbow 16b is some distance above the plane 19 at the open neck of the bag. The purpose of this arrangement is that if water fills to the top of the bag it will overflow at the plane 19 before it reaches the open end of the elbow 16b.

Referring now to Figs. 1 and 2, the sleeve 18 is provided with an opening 18a which is adapted to be closed or opened by a valve 20. This valve is mounted on a stem 21 which in turn is pivotally mounted to a bell crank 22 which in turn is pivotally mounted at 23 on the cover 12. The other arm of the bell crank carries a roller 24 which rests upon the rubber tubing 16. A coiled helical spring 25 is held between the guide bracket 26 and the head of the valve 20 to urge the valve toward closed position and to urge the roller 24 into contact with the rubber tubing 16. The chamber 27 between the cover 12 and the inner cover 15 is vented to atmosphere through an opening 28.

The operation of my device should now be apparent. Normally rubber tubing 16 is flat at the zone 16a as shown in Fig. 4 and the roller 24 in engagement therewith permits the spring 25 to close the valve 20. Each time water flows through the tube 16 under the control of a suitable solenoid valve as disclosed in my copending application, Serial No. 5,619, filed January 31, 1948, the stream of water will fill the tube causing the same to expand to the positions shown in Figs. 2 and 3. This will move the roller 24 in a counterclockwise direction about the pivot 23

and will pull upon the stem 21 to open valve 20 against the bias of spring 25. The result of this operation will be more fully appreciated from a consideration of my copending application, for an automatic washing machine, Serial No. 5,619, filed January 31, 1948, which illustrates how after a washing operation, two rinsing operations take place automatically and sequentially. After the washing operation, a vacuum is created within the bag 10 causing the bag to collapse against the wet laundry to squeeze the water out of the same. At the close of this squeezing operation the bag and everything in communication with it is under a partial vacuum of a very high nature. It is then desirable to break this vacuum before the rinse water runs into the bag because otherwise the rinse water might fill up clear to the level of the elbow 16b in order to fill the vacuum. This might result in contamination, of the supply entering through the line 16 if a vacuum should occur in this supply line at such a time. This is obviated by my invention wherein the incoming rinse water in the tube 16 will automatically open the valve 20 which will vent the bag through the sleeve 18, the opening 18a and the opening 28a to atmosphere. When there is no water flowing in the tube 16 then the valve 20 is closed and the machine will operate exactly as described in my above mentioned copending application.

I claim:

1. In a washing machine having a flexible liquid- and air-tight bag within which laundry and liquid detergent may be placed and having means for withdrawing liquid and air from the interior of said bag creating a substantial vacuum therein to cause the latter to collapse against the laundry to squeeze out the detergent by pressure on the outside of said bag, said bag having an open neck and a cover closing said neck, there being a planar seal between said bag neck and said cover permitting fluid flow outwardly only, a passageway communicating between the interior of said bag and atmosphere, a valve controlling flow in said passageway, a conduit for introducing liquid into said bag, said conduit terminating above the plane of said seal, and an operative connection for said valve responsive to liquid flow into said bag and so constructed and arranged that it opens said valve responsive to said liquid flow to release said vacuum.

2. The combination of claim 1, wherein said conduit includes a resilient portion normally self-closing and expandible by liquid flow in said conduit, and said operative connection includes a member operable by expansion of said resilient portion.

3. In a machine for washing materials comprising a flexible liquid- and air-tight bag having an aperture providing communication between the interior thereof and the atmosphere, means for creating a vacuum in said bag to squeeze-dry said materials, means to break said vacuum comprising a flexible tubular element to admit fluid to said bag having a passageway therethrough, said passageway being normally closed by contraction of the walls thereof and adapted to open by expansion of the walls thereof upon admission of fluid therethrough, and a valve means responsive to the opening and closing of said passageway, whereby said aperture is closed, when said passageway is closed, and said aperture is opened when said passageway is open.

4. In a washing machine having a flexible liquid- and air-tight bag within which laundry

and liquid detergent may be placed and having means for withdrawing liquid and air from the interior of said bag creating a substantial vacuum therein to cause the latter to collapse against the laundry to squeeze out the detergent by atmospheric pressure on the outside of the bag, a passageway communicating between the interior of said bag and atmosphere, a valve controlling flow in said passageway, means for introducing liquid into said bag including a conduit having a resilient portion normally self-closing and expandible by liquid flow into said conduit, and an operable connection for said valve responsive to liquid flow into said bag, said connection including a member operable by expansion of said resilient portion, said connection being so constructed and arranged that it opens said valve responsive to said liquid flow to release said vacuum.

5. In a combined washing and extracting machine of the type employing a flexible liquid- and air-tight bag in which the washing means is located and having successive requirements for filling said bag with liquid for washing and collapsing of said bag by vacuum for extraction, said bag having a passageway, a vacuum breaker characterized by a valve actuated to open and close said passageway to said bag, said passageway communicating with the atmosphere, means for maintaining said valve in normally closed position during collapsing of said bag by vacuum, inlet means comprising a conduit for admitting liquid under pressure to said bag for washing and rinsing, and means responsive to fluid pressure in said conduit to open said valve.

6. In a combined washing and extracting machine of the type employing a flexible liquid- and air-tight bag in which the washing means is located and having successive requirements for filling said bag with liquid for washing and collapsing of said bag by vacuum for extraction, said bag having a passageway, a vacuum breaker characterized by a valve actuated to open and close said passageway to said bag, said passageway communicating with the atmosphere, means for biasing said valve in a normally closed position, inlet means comprising a conduit for admitting liquid under pressure to said bag for washing and rinsing, and means responsive to fluid pressure in said conduit to open said valve.

7. In a combined washing and extracting machine of the type employing a flexible liquid- and air-tight bag in which the washing means is located and having successive requirements for filling said bag with liquid for washing and collapsing of said bag by vacuum for extraction, said bag having a passageway, a vacuum breaker characterized by a valve actuated to open and close said passageway to said bag, said passageway communicating with the atmosphere, a spring means biasing said valve to closed position, inlet means comprising a conduit for admitting liquid under pressure to said bag for washing and rinsing, and means responsive to fluid pressure in said conduit to open said valve.

8. In a combined washing and extracting machine of the type employing a flexible liquid- and air-tight bag in which the washing means is located and having successive requirements for filling said bag with liquid for washing and collapsing of said bag by vacuum for extraction, said bag having a passageway, a vacuum breaker characterized by a valve actuated to open and close said passageway to said bag, said passageway communicating with the atmosphere means

for biasing said valve to closed position, inlet means comprising a conduit having a flexible portion for admitting liquid under pressure to said bag for washing and rinsing, and means responsive to fluid pressure in said flexible portion to open said valve.
